TOOL FOR SETTING SCREW-ANCHORS.

1,164,903.

Specification of Letters Patent. Patented Dec. 21, 1915.

Application filed March 20, 1915. Serial No. 15,981.

To all whom it may concern:

Be it known that we, CHARLES N. ACKERMAN and JOHN L. JOHNSON, citizens of the United States, residing at Chicago, in the county of Cook and State of Illinois, have invented certain new and useful Improvements in Tools for Setting Screw-Anchors, of which the following is a specification.

Our invention relates to a tool for setting 10 screw anchors and the like, and in some of its features particularly to a driving tool for such purpose.

A particular object of our invention is to provide a driving tool for setting a screw 15 anchor that consists of an externally tapered, screw receiving body surrounded by a ductile sleeve that may be distorted or swaged to wedge between the rigid body and the peripheral wall of an anchor-receiving recess.

Particular objects of our invention are to provide a tool that may be most facilely employed for the swaging or distortion of the ductile sleeve, that will insure proper 25 and uniform application of the setting force to all portions of the sleeve; that will tend to prevent distortion of the sleeve in such fashion as to interfere with the thread bore of the body; and that will otherwise aid 30 in the best setting of the anchor.

In the drawings wherein we have illustrated embodiments of our invention for purposes of full disclosure thereof, Figure 1 is a broken view showing a fragment of a 35 tool embodying our invention in association with a screw anchor to be set. Figs. 2 and 3 illustrate by similar broken views the intended use of the tool. Fig. 4 is a sectional view showing a modified tool embodying our 40 invention, illustrated in coacting relation with an anchor and Figs. 5 and 6 illustrate in sectional view and in elevation an anchorage device as it may be set by the use of said tool.

A screw anchor of the sort above suggested is illustrated as comprising a body 10, and a sleeve 14. The body 10 is preferably rigid, made of brass or steel, with a screw receiving bore 11 made axially through its 45 front end and opening into a bell or conical recess 11' at the rear end. Said body is externally tapered toward its front end, preferably with a slight pitch 12 through-

out the major portion of its length and with a more abrupt pitch 13 adjacent the bell recessed end thereof, so giving a biconoidal effect. The ductile sleeve 14, surrounding body 10, is preferably of lead, and preferably is sufficiently wedged on the body, preliminarily, to be handled therewith as a unit. 55 Such sleeve is preferably cylindrical externally and of about the maximum diameter of the body, and has a normal bore 15 of approximately the diameter of the front extremity of the body. Before distortion the sleeve overhangs the front end of the anchor and stops short of the rear end—preferably near the beginning of abrupt pitch 13. Such a screw receptive anchor may be seated in a recess 16 in a structure 17 by 60 placing the anchor device in the recess so that the rear end of the body rests against the bottom 18 of the recess and then applying force to the ductile sleeve 14 to force it along the flaring body, so to enlarge its 65 diameter that it will grip against the side walls of said recess. It is for this last named purpose that our tool, indicated in general at 20, is employed. Said tool, in the form shown in Figs. 1 to 3, comprises a body 21 70 of diameter suitable to make it convenient for hand grasp, having an end 22 suitable to resist hammering, and having its forward or acting end constructed for coöperation with the anchor. This acting end comprises 75 a pressure surface 23 of annular form, with its inner diameter somewhat larger than the smallest exterior diameter of the body 10 of the anchor and with its exterior diameter 80 preferably approximately equal to the normal diameter of the externally cylindrical sleeve 14. Within this annulus and concentric therewith is a pilot 24, externally smooth, normally protruding beyond the pressure surface 23, and of smaller diameter 85 adequate to slip neatly within the screw threaded bore 11 of the anchor. Thus there is left between the pilot and the pressure surface a clearance space 25 within the body 90 slightly wider than the front end of the body 10 of the anchor.

It is preferable, (although it is not essential,) that the pressure surface shall have small recesses 26 (or projections) that may take the form of suitable lettering or the 95 like.

In using the tool the pilot is slipped into the screw bore 11, and the tool may thus be used as an implement for inserting the anchor structure into its recess in the wall.

5 When the anchor is bottomed in the socket, the end 22 of the tool is hammered upon, driving the ductile sleeve rearwardly on the flaring rigid body and so spreading it laterally until it exerts a firm lateral grip upon

10 the encompassing walls of the recess 16. By accurate work in drilling the recesses of suitable diameter, and just the depth of the anchor body in material of uniform density, such as slate or metal, the anchors

15 may be made to exert an effective grip just when the ductile sleeve is swaged in substantially flush with the end of the socket and with the end of the body 10, as shown in Figs. 2 and 6. But it often happens,

20 owing to oversizing of the recess diameters, irregularity in the contour of the recess, and other causes, that in order to exert the required grip the lead must be swaged beyond this ideal point, producing a result some-

25 what as shown in Fig. 3, and it will be observed that the provision of a clearance space 25, somewhat larger than the anchor-body-end and running back into the body 21 of the tool, enables the pressure surface

30 of the tool to be advanced well over the tapered end of the body 10 of the anchor to complete the desired swaging operation.

In Fig. 4 the modified embodiment shown has its pilot 24' projecting from a yielding

35 filler-block 26 that nearly fills the clearance space 25' in the body of the tool, said block 26 working against the spring 27 and the front end of the block affording an annular shoulder 28 that may abut against the

40 end of the anchor body 10. The operation of this form of tool will be the same as has heretofore been described, save that the pilot 24' does not move with the tool body after the hammering operation commences,

45 but maintains its relation to anchor body 10 and therefore yields relative to the tool body as the latter advances. It will be seen, of course, that the pilot-carrying block may retreat into the body 21' so that the clear-

50 ance space 25' within the body may pass over the forward end of the anchor body 10 as heretofore described. It will be apparent that this last mentioned form of device provides in its portion 26 a filler that will pre-

55 vent radial inflow of the metal of the ductile sleeve to such point as possibly to interfere with the freedom of the end of anchor body 10; and for this reason it is a particularly desirable form for use in some

60 cases where the anchor initially fits very snugly in its recess and swaging to produce a very tight grip of the anchor is desired. However, we find in practice that the simpler form of construction, shown in

Figs. 1 to 3, is efficacious for most purposes, 65 and is commercially desirable for its cheapness.

It will be observed that the normally-protruding pilot, effecting preliminarily a relatively long bearing in the screw bore, not 70 only enables the anchor to be conveniently handled, for insertion in any position, (particularly in an overhead position) but also insures that the swaging drive will be directly axial with respect to the anchor and 75 that uniform application of the driving force on all parts of the forward end of the ductile sleeve will be effected. In practice this is important, for any diagonal presentation of the pressure surface to the end of the ductile sleeve that would inevitably result in forcing the portion of the sleeve on which the unbalanced driving force was exerted inwardly toward the screw bore. Also the provision of recesses (or projections) 80 on the pressure surface insures that during the setting operation there will be an appreciable friction tendency between the sleeve and tool to hold the tool in continuing contact with the sleeve surface, owing 85 to the swaging of the metal into the recesses, and also an appreciable tendency to prevent any rotary movement of the pilot in the threaded bore, that might tend to grind or distort the crests of the screw 90 thread teeth.

While we have herein described in some detail a particular embodiment of our invention in a driving tool it will be understood that in its broader aspects many 100 changes in the construction might be made without departure from the spirit of our invention and within the scope of the appended claims.

Having described our invention, what we 105 claim is:

1. A setting tool for screw anchors comprising a pressure portion for swaging and a normally-protruding pilot portion for guidance, there being between the outer periphery of the pilot and inner periphery of the pressure surface a clearance space extending back into the body of the tool.

2. A tool of the character described comprising a body portion having an end adapted to be hammer driven, and an opposite end providing an annular pressure surface, and a pilot protruding beyond said pressure surface, centrally located with respect thereto, and spaced apart therefrom.

3. A setting tool for screw anchors comprising a body having an annular pressure surface at one end, and a clearance space within said pressure surface, and a pilot adapted to engage the anchor bore, located centrally within the clearance space.

4. An anchor-setting tool of the character described comprising a body having a pres-

sure surface for swaging, and a smooth, cylindrical, normally-protruding pilot portion for guidance, there being between the pilot and the pressure surface an annular clearance space extending back into the body of the tool, and adapted to receive the end of an anchor.

In testimony whereof we hereunto set our hands.

CHARLES N. ACKERMAN.
JOHN L. JOHNSON.
